UNITED STATES PATENT OFFICE

168,053

FOLDING CAN AND BOTTLE OPENER

Michael J. Laforte, Park Ridge, Ill., assignor to Vaughan Mfg. Co., Chicago, Ill., a corporation of Illinois

Application April 18, 1952, Serial No. 19,383

Term of patent 14 years

(Cl. D44—29)

To all whom it may concern:

Be it known that I, Michael J. Laforte, a citizen of the United States, residing at Park Ridge, in the county of Cook and State of Illinois, have invented a new, original, and ornamental Design for a Folding Can and Bottle Opener, of which the following is a specification, reference being had to the accompanying drawing, forming part thereof.

Fig. 1 is a top plan view of a folding can and bottle opener, embodying my new design.

Fig. 2 is a side elevational view.

Fig. 3 is a bottom plan view.

Fig. 4 is an end elevation looking at the tool from the right side of Fig. 2; and

Fig. 5 is a side elevation similar to Fig. 2, showing, however, the tool unfolded.

I claim:

The ornamental design for a folding can and bottle opener, substantially as shown.

MICHAEL J. LAFORTE.
